COMBINED PORTABLE TAPE DECK AND
SPEAKER SYSTEM OR SIMILAR ARTICLE

Lester M. Moffet, 30427 1st Place S.,
Federal Way, Wash. 98002

Filed July 3, 1972, Ser. No. 268,773

Term of patent 14 years

Int. Cl. D14—03

U.S. Cl. D26—14 B

FIG. 1 is an isometric view of a combined portable tape deck and speaker system showing my design;

FIG. 2 is a front elevation view;

FIG. 3 is a right end elevation view, the left end being identical in appearance to the right end; and

FIG. 4 is a back elevation view.

I claim:

The ornamental design for a combined portable tape deck and speaker system or similar article, as shown and described.
